United States Patent Office

Des. 194,507
Patented Feb. 5, 1963

194,507

COMBINED FLOWER AND CANDLE HOLDER OR THE LIKE

Walter A. Saxe, Albany, N.Y., assignor to Saxe Brothers,
Inc., Albany, N.Y., a corporation of New York

Filed May 11, 1962, Ser. No. 70,086

Term of patent 14 years

(Cl. D35—3)

FIG. 1.

FIG. 2.

FIG. 3.

FIG. 1 is a top plan view of the combined flower and candle holder or the like embodying my new design;

FIG. 2 is a front elevational view thereof; and

FIG. 3 is a front perspective view thereof.

The undisclosed sides of the combined flower and candle holder or the like are substantially the same in appearance as the front shown.

I claim:

The ornamental design for a combined flower and candle holder or the like, as shown and described.
